UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

MANUFACTURE OF HEELS.

Application filed October 19, 1918. Serial No. 258,849.

This invention relates to the manufacture of heels for boots and shoes and comprises both a method of operation and an improved machine for making heels.

5 The object of the invention is to provide an improved method and a novel machine, by the employment of which the largest possible production may be secured and maintained with a reduced number of operatives 10 and with a minimum requirement for skill from such operatives.

In the commercial production of heels the lifts are assembled into piles and secured together to form heel blanks, which are afterward subjected to great pressure in a closed mold to solidify and shape the blanks. The molding, or compressing, operation is performed rapidly, while the assembling of the lifts, commonly called heel building, is a 20 relatively slow operation. Several heel building operatives are, therefore, required to keep one compressor operative busy.

In the accomplishment of the stated object, with the above outlined conditions in 25 view, the invention provides an improved method of operation according to which lifts are assembled to form heel blanks simultaneously at a plurality of assembling points, the completed blanks from the several assembling points being placed in a single, unbroken row which is continuously 30 conveyed to a single compressing station where the blanks are continuously delivered one by one from the forward end of the row 35 and subjected to compression uninterruptedly, producing a continuous flow of compressed or molded heels.

In order to carry out the method most effectively it is advantageous to use a system 40 of heel making machinery in which heel building machines, a heel compressing machine and automatic transferring mechanism are combined in one organization. A battery of heel building machines and an automatic heel compressing machine having a 45 productive capacity as great as that of all the heel building machines are connected by transferring mechanism having transferring capacity as great as that of the entire battery of heel building machines to provide 50 for transferring all the heels away from the heel building machines as fast as they are built and delivering them to the compress-

ing machine in an uninterrupted regular sequence which provides heels for the compressing machine as fast as it can operate upon them and dispenses with the operatives heretofore employed to feed the blanks to the compressing machine and to collect the blanks from the builders and deliver them to the compressing machine. The transferring mechanism may advantageously be driven by the automatic compressing machine, thus insuring its operation in proper time relation thereto.

55 In this connection, a further feature of the invention relates to improved means for driving the carrier from the vertically moving mold carrying cross head of the compressor, this being preferably effected by supporting one portion of the carrier upon stationary brackets upon the frame of the compressor and transmitting movement from the moving cross head of the compressor to advance the carrier step by step.

60 Other features and advantages of the invention will become apparent when reading the following detailed description of one embodiment thereof in connection with the accompanying drawings, in which:

65 Figure 1 is a view in front elevation showing a heel compressor, a heel building machine and portions of the connecting heel guide and transferring carrier;

70 Fig. 2 is a view in continuation of Fig. 1, showing the remaining building machines in their relation to the carrier;

75 Fig. 3 is a perspective view of the mechanism for driving the endless chain carrier from the cross head of the compressor;

80 Fig. 4 is a vertical longitudinal section of a portion of the compressing machine illustrating the delivery thereto of a heel blank; and

85 Fig. 5 is a perspective view of a detail of the adjusting mechanism for the heel guide.

90 10 indicates the frame of an automatic heel compressing machine which may, for example, be of the type shown and described in Letters Patent No. 1,172,471, granted Feb. 22, 1916, upon the application of Thomas Lund.

95 A, B, C and D indicate four similar building machines which may be of the type disclosed in United States Letters Patent No. 1,056,720, granted Mar. 18, 1913, upon

the application of Eliphilet A. Tripp. Brackets 12 upon the frames of the heel building machines support an elongated guide 14 in which runs a heel transferring carrier consisting of parallel endless chains 16 connected at suitably spaced intervals by cross bars 18 between which heels may be placed on the guide 14. The series of heel building machines and the heel compressing machine are all in alinement in order that the carrier may move in a straight line to conduct heels from all the building machines and deliver them to the compressor.

Beyond the first building machine, the carrier passes over an idle sprocket 20 which may be adjusted by means of a screw 22 to keep the chain taut. At the opposite end of its path the carrier passes over a driving sprocket 24 and an idle guide pulley 26, both of which are mounted to rotate in a stationary bracket 28 bolted to the frame of the compressor.

The compressor has the usual vertically reciprocating cross head 30 carrying the compressing mold 32 and provided with a forwardly projecting bracket 34 for supporting and guiding the feed slide 36 which reciprocates forwardly and rearwardly to feed the heels to the compressing mold. The driving sprocket 24 is rotated step by step to deposit one heel at a time upon the feed slide. To this end, a ratchet wheel 38 is secured to the shaft 40, upon which the driving sprocket is also secured. A rocker arm 42 loosely mounted upon the said shaft 40 has pivoted to its outer end a spring actuated pawl 44 arranged to engage the teeth of the ratchet 38. Also pivotally connected to the end of the arm 42 is a link 46, the lower end of which is connected to the free end of a lever 48 having its opposite end pivoted to the machine frame at 50. A roll 52 is mounted in the center portion of the lever 48 in the path of a plunger 54 resting upon a substantial spring 56 contained in a cylinder 58 carried by a bracket 60 bolted to the cross head 30. A light spring 62, connected at one end to the lever 48 and at the other end to a pin 64 in the cylinder 58, tends to draw the link 46 and the arm 42 downward but, when the cross head 30 rises, an adjustable plug 66 in the upper end of the plunger engages the roll 52, rocking the arm 42 about its axis and, through the pawl and ratchet, rotating the sprocket 24 sufficiently to advance the carrier chain one space. An adjustable holding pawl 67 engaging the ratchet teeth prevents reverse rotation. In the event of an obstruction retarding the movement of the carrier the spring 56 will yield to prevent breakage of any of the mechanism. This spring, however, is stiff enough and is normally held under sufficient tension so that in the ordinary operation of the machine it does not yield. In the down-

ward movement of the cross head the pawl is retracted by the spring 62 until an abutment 68 upon the lever 48 engages the side of the bracket 28, after which, the plug 66 leaves the roll 52 and the pawl arm remains stationary.

As will be more clearly described herein-after, the blanks produced by the heel building machines are deposited upon the guide member 14 between the cross bars 18 of the transferring carrier. The step by step advance of the carrier causes the heels to be advanced to the end of the guide adjacent to the compressor where a hinged portion 72 guides them to a point from which they drop upon a plate 74 supported by a bracket 76, bolted to the bracket 34. This position of the heel blank is shown at 78 in Fig. 4.

The deposit of the blank upon the plate 74 as a result of the movement of the carrier occurs at the end of the upward movement of the cross head 30, at which time the feed slide 36 is in its outermost position. A pusher 80, adjustably secured to the feed slide by a set screw 82, engages the blank upon the next inward movement of the feed slide (in the downward movement of the cross head) pushing the blank off the plate 74 and depositing it upon a plate 84 which is secured to the feed slide and moves therewith, it being understood that, at the time of the deposit of the blank upon it, the plate 84 is at the left of the plate 74. During the next upward movement of the cross head and consequent retraction of the feed slide, the plate 84 is withdrawn from beneath the blank, which then drops into the position indicated at 86 between the clamping jaws 88 of the feed slide. In the next inward movement of the slide the jaws carry the blank into compressing position and deposit it at 90 in the compressing mold. A resilient finger 91 supported just above the path of the blanks insures that they shall be kept under control as they are fed to the compressing machine.

In order to insure an accurate positioning of the blank as it leaves the guide 14, members 92, 94 are provided to guide it and prevent its misplacement transversely. The side guide 92 is stationary while the side guide 94 is supported loosely upon the member 14 and is engaged near either end by pins 96 mounted in disks 98 secured to short vertical shafts 100 having crank arms 102 secured to their lower ends. The outer ends of the two crank arms 102 are connected by a rod 104 which may be manually moved lengthwise to turn the disks 98 to effect adjustment of the space between the members 92, 94. It will be observed that the right-hand end of the rod 104 and the adjusting member to which it is connected are located within easy reach of the operative of the last heel building machine D of the series. After

the desired adjustment is effected, the rod is secured against accidental movement by a set screw 106.

The heel compressing machine is started by depressing the usual treadle 108 against the tension of a spring 110. A locking latch 112 pivoted to the machine frame at 114 is under the influence of a spring 116 and is provided with a shoulder 118 arranged to engage a portion 120 of the treadle and lock the latter in running position. A rod 122 connects the latch 112 with a pedal 124 located within reach of the operative of the heel building machine D. Thus, when the machine is in operation, this operative is able, by depressing the pedal 124, to withdraw the latch 112, permitting the treadle 108 to rise and causing the heel compressing machine and heel transferring carrier to stop.

The operation is as follows: Assuming the compressing machine and heel carrier to be running, heels are built in the heel building machines A, B, C, D and deposited in the carrier. The operatives of machines A, B and C need pay no special attention to the particular spaces of the carrier in which their heels are deposited, merely placing the heels as fast as they are produced in any accessible vacant space in the chain. The operative of machine D, which is the last machine in the series and is next to the heel compressor, may act in a supervisory capacity, it being her duty to see that any spaces not filled by the previous machines of the series are supplied with heels. As will be apparent, she also, through pedal 124, has control of the compressing machine and, consequently, of the movement of the carrier, being able, in the event of any serious disarrangement or failure to keep the carrier supplied with heels, to stop the entire transferring and compressing system immediately. It is preferable that the best operative be placed at machine D since her requirements are subject to variation, and closer attention is required upon her part than upon the part of the other operatives in the series. It has been found under actual commercial conditions, however, that by using the proper number of heel building machines with relation to the style of heel being produced, the production of the unit may very readily be adjusted to the requirements of the compressor and that all the operatives may work continuously, producing heels at a maximum rate without undue strain or tension. The services of the usual operative for feeding the heel compressing machine are dispensed with entirely, as is also the boy commonly employed for gathering up the heels from the various builders and supplying them to the operative of the compressing machine. It will thus be apparent that I have effected an organization

of machinery by the use of which the product of the labor of a given number of operatives is greatly increased, or conversely, a given quantity of work is produced with a substantially smaller number of workers.

It should be understood that the descriptive terms "automatic" and "non-automatic", used herein with relation to the compressing machine and the building machines denote respectively devices which are completely automatic in operation, not requiring the services of an operative, and those which are not completely automatic but do require the services of an operative.

Having described my invention, what I claim as new and desire to secure by Letters Patent of the United States is:—

1. The method of manufacturing compressed or molded heels, which consists in simultaneously assembling heel lifts into piles to form completed heel blanks at a plurality of assembling points, maintaining the heel lifts in assembled relation, continuously placing the completed blanks from the several assembling points in a single unbroken row, continuously conveying the said row to a single compressing station, continuously delivering the blanks one by one from the forward end of the row to a single compressing means and subjecting the successive blanks to compression uninterruptedly.

2. The method of manufacturing compressed or molded heels which consists in simultaneously assembling heel lifts into piles at a plurality of assembling points at such rates of speed as to sustain a substantially uniform, predetermined rate of total production, securing the lifts of each pile together as fast as the piles are assembled, to form heel blanks, continuously placing the blanks thus formed at the several assembling points in a single unbroken row, continuously conveying the said row to a single compressing station, continuously delivering the blanks one by one from the forward end of the row to a single compressing means at the same predetermined rate as said rate of total production, and subjecting the successive blanks to compression uninterruptedly.

3. The method of manufacturing compressed or molded heels, which consists in simultaneously assembling heel lifts into piles to form heel blanks at a plurality of assembling points at undetermined individual rates of speed, continuously placing the blanks from the several assembling points, as fast as they are produced, in a broken row, simultaneously assembling lifts to form blanks at an additional assembling point at a variable, controlled rate which results in a substantially uniform, predetermined total rate of production from all the assembling points, completing the broken row of blanks by placing in the gaps therein the blanks

produced at said additional assembling point, continuously conveying the said row to a single compressing station, continuously delivering the blanks one by one from the forward end of the row to a single compressing means and subjecting the successive blanks to compression uninterruptedly.

4. The combination with a heel compressing machine having a vertically moving cross head and a feed slide carried thereby, of an endless chain carrier operated by vertical movement of the cross head for transferring heels to the feed slide.

5. The combination with a heel compressing machine having a vertically moving cross head and a feed slide, of an endless chain heel carrier supported upon station-

ary brackets upon the machine and constructed and arranged to deliver heels one at a time to the feed slide, and means operated by vertical movement of the cross head for advancing the carrier step by step to deposit a heel upon the feed slide at each vertical movement of the cross head.

6. The combination, with a heel compressing machine having a vertically moving cross head and horizontally moving feeding mechanism, of an endless chain mechanical feeder operated by movement of the cross head and moving transversely of said feeding mechanism to deliver heels thereto.

In testimony whereof I have signed my name to this specification.

THOMAS LUND.
